UNITED STATES PATENT OFFICE.

ISRAEL BENJAMINS, OF BROOKLYN, NEW YORK, ASSIGNOR TO MARK & MOHL, INC., OF BROOKLYN, NEW YORK, A FIRM.

GRATING.

1,140,657.

Specification of Letters Patent.

Patented May 25, 1915.

Application filed June 9, 1914. Serial No. 844,101.

To all whom it may concern:

Be it known that I, ISRAEL BENJAMINS, a citizen of the United States, residing at 161 Division avenue, Brooklyn, in the county of 5 Kings and State of New York, have invented a new and useful Grating, of which the following is a specification.

My invention relates to improvements in gratings used for areaways, sidewalk openings, subway coverings, fire-escape treads and platforms, stair treads and platforms, guards for windows or openings in walls, openings in interiors of structures and for similar purposes; it consists in the novel 15 features hereinafter more fully described and illustrated in the drawings.

The objects of my improvement are: first, to produce a grating of great strength and durability with a minimum of expense 20 of material and labor; second, to produce a grating of attractive appearance; third, to produce a grating, which is comparatively free from dirt and obstructions accumulating in its passages and between its bars. I 25 attain these objects by the grating, one form of which is illustrated in the accompanying drawings, in which—

Figure 1 is a plan; Fig. 2 is an elevation or side view; Fig. 3 is an end view; Fig. 4 30 is an elevation of the detail 12; Fig. 5 is a plan or top view of the said detail 12; Fig. 6 is an elevation of the detail 13 in its original shape; Fig. 7 is an end view of said detail 13; Fig. 8 shows a sectional view 35 of details 12 and 13 in position and part of detail 11 in elevation; Fig. 9 is an elevation of part of detail 11 showing clearly the form of slots punched or otherwise formed in it.

Similar letters and numerals refer to 40 similar parts throughout the several views.

My grating as shown is formed of three sets of bars, as follows: 1. Longitudinal or bearer bars 11 having slots 15 and enlargements 15^a of the same slots near their lower 45 ends; 2. transverse or spacing bars 12 having notches 14 and 14^a in their upper edges, the depth of said notches being equal to the depth of the bridge-strips 16 of the bars 50 11, as shown; 3. key-bars 13, which are deformed into the shape 13^a by pressure or hammering after they are placed in position.

To assemble the grating the bars 12 are 55 first passed through the slots 15—15^a and

then raised vertically until their notches 14 and 14^a will coincide with the bridge strips 16 of the bars 11; the key-bars 13 are then inserted into the enlarged slots 15^a of bars 11 under the bars 12, and finally, to make 60 the structure rigid, the key-bars 13 are pressed or hammered on the sides, thereby causing them to expand vertically and press against the lower edges of bars 12 above them and on the bottoms of the slots 15^a in 65 bars 11, thereby rendering the structure of the entire grating tight and secure. The bars 13 of Figs. 6 and 7 will in this way be deformed into a shape similar to that of 13^a shown in Fig. 8.

Numerous modifications could be made in my grating without departing from the main scope of my invention.

Instead of being initially round as shown in the drawings the key-bars 13 may have 75 any suitable cross-section in all cases, such as square, rectangular, hexagonal, semicircular and others.

The spacing bars 12 and slots 15—15^a could also be varied in shape, if desired. 80

The key-bars could be placed in the side of the spacing bars, instead of being underneath the same, and the slots may then be formed accordingly.

I do not therefore restrict myself to the 85 exact shape of my grating as shown in the drawing, nor to the exact shape of any of the details shown; but I intend to include all mechanical equivalents and obvious modifications of the same.

What I claim as my invention and desire 90 to secure by Letters Patent is:—

1. A grating comprising bearer bars having suitable slots, spacing bars and key-bars passing through said slots, said key-bars having portions, inclosed between said bearer bars, expanded in the direction of said spacing bars, thereby securing said spacing bars in position.

2. A grating comprising bearer bars having suitable slots, spacing bars and key-bars passing through said slots, said key-bars being situated under said spacing bars, when the said grating is horizontal, and having portions, inclosed between said 105 bearer bars, expanded vertically, thereby securing said spacing bars in position.

3. A grating comprising bearer bars, spacing bars and keybars, said bearer bars having slots enlarged at their lower ends, 110

when said grating is horizontal, said spacing bars passing through the upper ends of said slots, said keybars, being initially thicker than said spacing bars, passing through said enlargements in said slots and having portions, inclosed between said bearer bars, expanded vertically by compressing the sides of said keybars after the said spacing bars are in place, thereby securing said spacing bars in position.

4. A grating comprising bearer bars, spacing bars and keybars, said bearer bars having slots, said spacing bars and keybars

passing through said slots, said keybars, being initially round, having portions inclosed between said bearer bars expanded in the direction of said spacing bars by compressing the suitable sides of said keybars after the said spacing bars are in place, thereby securing said spacing bars in position.

ISRAEL BENJAMINS.
